INVENTOR

Joseph Muros

BY

T. F. Bourne

ATTORNEY

UNITED STATES PATENT OFFICE

JOSEPH MUROS, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed May 8, 1931. Serial No. 535,899.

My invention has reference to safety razors comprising blade clamping members having means to enter apertures in blades to position the latter in shaving relation to guarding means.

An object of my invention is to provide means to position a blade in shaving relation to guarding means in the event that the blade has an aperture that will not cooperate with the blade positioning means of the blade holder to retain the blade in shaving position.

In carrying out my invention I provide blade clamping members having blade positioning means, a handle detachably connected with said members, and blade positioning means retained between a blade clamping member and the handle, said positioning means being cooperative with a blade to retain it in shaving position between the clamping members.

My invention also comprises novel details of improvement that will be more fully hereinafter set forth and then pointed out in the claims.

Reference is to be had to the accompanying drawing, wherein

Fig. 1 is a side view of my improved safety razor;

Fig. 2 is a section on line 2, 2 in Fig. 1;

Fig. 3 is a partly broken plan view of the razor taken on line 3, 3 in Fig. 2;

Fig. 4 is a section on line 4, 4 in Fig. 2;

Fig. 5 is a plan view of the blade positioning means or blade adapter;

Fig. 6 is a plan view of a blade;

Fig. 7 is a side view of a modification;

Fig. 8 is a cross section of Fig. 7 taken very close to the handle;

Fig. 9 is a plan view of the modified blade positioning means or blade adapter;

Fig. 10 is a section on line 10, 10 in Fig. 9, and

Fig. 11 is a plan view of the blade of Fig. 7.

Similar numerals indicate corresponding parts in the several views.

The numerals 1 and 2 indicate blade clamping members, the member 1 being shown as

50 a guard member having guard teeth on oppo-

site sides and the member 2 is shown as a blade cap or backing. The members 1 and 2 are adapted to clamp a blade 3 between them. At 4 is a handle detachably connected with the members 1 and 2. The handle 4 is 55 shown provided with a threaded recess 5 at one end adapted to mesh with a threaded stem 6 that projects from the cap 2 through an opening 7 in the guard member 1 into the recess 5, whereby the handle may be pressed or drawn toward the guard member. The members 1 and 2 are provided with blade 60 positioning means between them. I have shown the guard member 1 provided with spaced studs or projections 8, adapted to enter an aperture or apertures in a blade to position the latter on the guard member, and the cap or backing member 2 is shown provided with a projecting rib 9, (between the studs 8) adapted to pass through a blade 65 aperture. The cap 2 is shown provided with recesses 10 to receive the studs 8 from the guard member, and the guard member is shown provided with a recess 11 to receive the projecting rib 9 from the cap, whereby 70 the clamping members and the blade may be assembled as illustrated in Fig. 2. A blade having one or more apertures adapted to properly receive the projecting means 8 and 9 will be retained in shaving position 75 between the members 1 and 2 with the blade cutting edges in shaving relation to the guard teeth.

A blade having an aperture 3a that does 80 not properly fit the blade positioning means 8 and 9 would not be retained by said means in proper shaving relation to the guard teeth. In order to retain the blade having such an aperture, as 3a, in shaving relation to the 85 guard member I provide a blade positioner or adapter 12 having means to engage the blade and retain it in shaving relation to the guard. The adapter 12 is provided with one or more projections at its ends to engage 90 the blade to position it on the guard member. Said adapter is also provided with a hole 13, shown centrally disposed, adapted to receive the stem 6 of the cap 2. The adapter comprises a suitable piece or sheet of 95 100

metal adapted to fit against the outer surface of the guard member 1, on the side opposite the blade receiving surface of said member. When the adapter 12 is placed against the 5 guard member and the handle 4 is screwed on the stem 6, with the parts assembled as in Fig. 2, the adapter will be retained between the guard member and the handle by screwing the latter tightly against the adapter.

10 In the form shown in Figs. 1 to 5 the adapter is provided with spaced projections 14 at each end that project toward the cap 2 sufficiently far to cooperate with the blade 3 to retain it in shaving position between the 15 members 1 and 2. The blade is shown provided with projections 3b at its ends, that are of less length transversely of the blade than the distance between the cutting edges of the blade, the blade having recesses 3' at 20 its corners. When the parts are assembled the adapter projections 14 will be at the ends of the guard member and in the recesses 3' of the blade, the end projections 3b of the blade opposing said projections 14, whereby the 25 blade will be retained on the guard member in shaving relation thereto.

Side portions of the adapter 12 are in position to engage the guard teeth 1a on the guard member 1 to locate the adapter in shaving relation to the guard member. I have shown the adapter provided with side projections 12a to engage the inner side of the guard teeth 1a to keep the adapter in position to locate the blade in shaving position 30 on the guard member. I preferably provide spaces 12b along the side of the adapter, between the corresponding projections 12a, as clearances or passages for lather from 35 between the guard teeth during shaving.

40 In the event that a blade cap or backing member is not retained in shaving position by a guard member of a blade holder, I prefer to make the projections 14 sufficiently long to oppose the ends of the cap or backing member 2 and engage the cap to locate the latter in shaving position on the blade.

45 In the form shown in Figs. 7 to 10 the adapter 12 is provided with a single projection 14 at each end, in the line of the longitudinal centre of the adapter, to receive the ends of the guard member therebetween. The central portions 15 of the adapter 12 are shown recessed, preferably being curved on a suitable radius, to receive a corresponding 50 projecting portion 16 extending longitudinally along the under side of the guard member, whereby when the parts are assembled the projection will extend into the recess 15. The central portion 17 of the adapter is flat 55 to bear against the guard member and the handle. The projections 3b of the blade are shown provided with recesses 3" to receive the projections 14 from the adapter to retain the blade cutting edges in shaving relation to the guard teeth. The projections 14

will engage the cap for the purposes before described.

When the razor is to be used with blades that are provided with apertures intended to fit the projectons 8 to retain the blade in shaving position on the guard member the adapter need not be used, and the handle 4 may be screwed directly against the guard member to clamp the blade between said member and the cap 2. When, however, a 70 blade having an aperture, such as 3a, not fitted to the projectons 8, is to be used in the razor the adapter will be placed against the under surface of the guard member, the blade will be placed on the guard member and the cap over the blade, and then the handle will be screwed on the stem 6 to retain the adapter, which will position said blade between the clamping members 1 and 2 in shaving position. 80

85 Changes may be made in the details set forth, within the scope of the appended claims, without departing from the spirit of my invention.

Having now described my invention what 90 I claim is:

1. A safety razor comprising blade clamp- 95 ing members, one of said members having a threaded stem and the other member having an opening to receive said stem, a handle hav- 100 ing means to detachably connect it with said stem, one of said members having blade position- 105 ing means, and an adapter for blades having a portion to fit one of said members for positioning the adapter with respect 110 thereto, said adapter having a hole to receive said stem with the handle bearing against the adapter to retain it against said member, said adapter having separate blade positioning means. 115

2. A safety razor as set forth in claim 1 in which the blade positioning means of the adapter includes projections at the ends of the adapter to engage a blade between said 120 members to retain the blade in shaving position. 125

3. A safety razor comprising blade clamp- 130 ing members having blade positioning means between them, a handle, one of said mem- 135 bers having a stem, means to detachably connect the handle and the stem, an adapter to fit against one of said members and having a hole to receive said stem, whereby the adapter may be clamped by the handle against said member, and a blade having an 140 aperture to receive said positioning means, said blade having projections at its ends and the adapter having projections at its ends to engage the projections of the blade to retain the blade in shaving position. 145

4. A safety razor as set forth in claim 3 in which the blade has recesses at its ends to receive the projections of the adapter. 150

5. A safety razor as set forth in claim 3 in which the blade projections are of less length 155

than the distance between cutting edges of the blade and the projections of the adapter are located at the ends of the blade projections.

5 6. An adapter for a safety razor blade holder having side portions to engage guard teeth of the holder to position the adapter to the holder, said adapter having means to locate a blade on the holder.

10 7. An adapter for a safety razor blade holder as set forth in claim 6 provided with recesses at its side portions to permit the passage of lather from the guard teeth.

8. A safety razor comprising a cap, a guard 15 with curved teeth along its edges, an interposed blade, and an adapter disposed outside the guard and equipped with portions for engaging and locating the adapter with respect to the inner curved face of the guard teeth 20 and separate projections for positioning the blade between the cap and guard.

9. An adapter for a safety razor which includes a guard member with curved guard teeth along each edge thereof, the adapter 25 comprising a plate fitting the outer face of the guard having lateral extensions for contacting with the guard teeth, and upright projections for positioning a blade upon the inner face of the guard.
